H. F. ROACH,
RAIL JOINT,
APPLICATION FILED AUG. 6, 1917.

1,258,252.

Patented Mar. 5, 1918.

Inventor,
Harry F. Roach,
By Bakewell & Churchattys.

UNITED STATES PATENT OFFICE.

HARRY F. ROACH, OF ST. LOUIS, MISSOURI.

RAIL-JOINT.

1,258,252.

Specification of Letters Patent. Patented Mar. 5, 1918.

Application filed August 6, 1917. Serial No. 184,653.

To all whom it may concern:

Be it known that I, HARRY F. ROACH, a citizen of the United States, residing at St. Louis, Missouri, have invented a certain new and useful Improvement in Rail-Joints, of which the following is a full, clear, and exact description, such as will enable others skilled in the art to which it appertains to make and use the same.

10 This invention relates to rail joints of the so-called "splice type," namely, joints in which splice members consisting of fish plates or angle bars are arranged on opposite sides of the webs of the rails in engagement with the heads and the base flanges of the rails.

15 In my pending application Serial No. 105,349, filed June 23, 1916, I have illustrated and described a rail joint of the general type referred to in which the side members of the joint have their end portions spaced away from the heads and the base flanges of the rails and their intermediate portions arranged in engagement with the heads and the base flanges of the rails so as 20 to form substantially hinge connections between the rails and the center portion of the joint which permit the wave motion of the rails throughout the track to be continued uniformly through the joints of the track.

25 30 In the rail joint described in said application the side members of the joint are arranged parallel to the rails and the intermediate portions of said members are wedged tightly between the heads and the base flanges of the rails throughout the entire length of said intermediate portions, thus forming relatively long bearing surfaces for the terminal portions of the rails at the center of the joint.

35 40 The main object of my present invention is to provide a rail joint of the general kind described in my application for patent above referred to, in which the side members of the joint are so constructed that a slight relief is provided for the terminals or extreme ends 45 of the rails at the center of the joint, thereby further reducing the stiffness of the portions of the rails that are embraced by the joint and also producing a more perfect hinge connection between the rails and the center portion 50 of the joint. Other objects and desirable features of my invention will be herein-after pointed out.

To this end I have devised a rail joint in 55 which the side members of the joint are so constructed and arranged that fulcrum

points will be provided for the rails at each side of the exact center of the joint and in proximity to the center bolts of the joint, the end portions of said side members being 60 spaced away from the heads and the base flanges of the rails, so as to permit the rails to move vertically at the ends of the joint under load, both upwardly and downwardly. The side members of the joint can either be 65 formed in such a manner that they do not contact with the heads and the base flanges of the rails at the terminals or extreme ends of the rails, or the side members can be so constructed and arranged that they provide 70 bearing surfaces for the terminal portions of the rails but still provide for a slight relief for the terminals or extreme ends of the rails when the rails are under load. I prefer to construct the joint in the manner last 75 described by using side members of similar form and design to those shown in my application previously referred to, but having their end portions drawn inwardly toward the webs of the rails, so as to cause the center portions of said side members to bow 80 out slightly, and thus produce fulcrum points on which the undersides of the heads and the upper sides of the base flanges of the rail bear at points a slight distance at either 85 side of the exact center of the joint.

Figure 1 of the drawings is a perspective view of a rail joint constructed in accordance with my invention; and

Fig. 2 is a view of said joint, partly in end 90 elevation and partly in vertical transverse section.

Referring to the drawings which illustrate the preferred form of my invention, A designates two members that are arranged 95 on opposite sides of two abutting rails B, and C and C' designate bolts or other suitable fastening devices that pass transversely through said members and through the webs of the rails. Each of the members A is provided intermediate its ends with means 1 and 2 that bear against the undersides of the heads 3 of the rails and against the upper sides of the base flanges 4, respectively, of the rails, said means 1 and 2 preferably consisting of integral portions on the upper and lower edges of each of the members A that extend a short distance on each side of the space between the ends of the rails. The end portions of each of the members A are 100 spaced away from the heads and from the base flanges of the rails, as shown in Fig. 105

110

1, so as to permit the rails B to deflect slightly and also move upwardly at the ends of the joint under load. By constructing the side members of the joint in this manner I 5 obtain practically hinge connections between the terminal portions of the rails and the center portion of the joint without the use of a base plate or supporting structure under the base flanges of the rails. When the 10 joint is in service the load imposed on one rail by a wheel traveling over the same will be transmitted to the center portion of the joint through the end of the rail, thus bringing the side members A into shear resistance at the center of the joint. When the 15 load passes from said rail onto the adjacent rail the load will be transmitted through the end portion of the rail to the center portions of the side members A in exactly the 20 same manner just described. It will thus be seen that in a rail joint of the kind herein illustrated the vertical bending moment of the side members A at the center of the joint is reduced to a negligible degree, so 25 that it is not necessary to consider the bending moment as a factor in designing a joint for the particular work that it is required to do. The hinge connection between the rails and the side members A of the joint eliminates hard spots in the track and prevents reverse strains from being created in the joint, as such a connection permits the wave motion 30 to pass through the joint uninterrupted. The side members A of the joint may be of 35 any preferred cross sectional shape and may be formed in various ways without departing from the spirit of my invention. In the form of my invention herein illustrated each of the side members A consists of a D-bar, 40 or bar of substantially D shape in cross section, whose center portion conforms substantially to the fishing section of the rails and whose end portions are of less depth or height than the vertical distance between 45 the heads and the base flanges of the rails, so that they will not bear against the same, the center portion of each of the side members A being so proportioned that when the 50 center bolts C of the joint are tightened the center portions of the side members A will be drawn inwardly into engagement with the heads and the base flanges of the rails, but not into engagement with the vertical webs of the rails, as indicated in Fig. 2. 55 During the installation of the joint the center bolts C are first tightened and thereafter the end bolts C' are drawn up tightly, so as to force the end portions of the side members A inwardly into snug engagement with 60 the vertical webs of the rails. As the center portions of the side members A are held spaced slightly away from the webs of the rails by the engagement of the surfaces 1 and 2 on the upper and lower edges of said 65 members with the heads and the base flanges

of the rails, it follows that when the end bolts C' are drawn up tightly the side members A will be slightly bowed out at the center of the joint, thus producing a slight relief α for the terminals or extreme ends of 70 the rails B, and consequently, causing the heads and base flanges of the rails to fulcrum on the side members A at points γ in proximity to the center bolts C of the joint when the rails are under load. The purpose 75 of constructing the joint in this manner is to further reduce the stiffness of the portions of the rails that are embraced by the side members of the joint and also produce a more perfect hinge connection between the 80 rails and the center portion of the joint, for when the joint is in service the rails will fulcrum on the points γ of the side members A, instead of on relatively long bearing surfaces that extend across the space between 85 the ends of the rails, as in the joint described in my application for patent previously referred to. In actual practice the upper and lower edges 1 and 2 of the intermediate portions of the side members A bear 90 against the undersides of the heads and against the upper sides of the base flanges of the rail, but the actual fulcrum points of the rails on the side members A are at the points γ , due to the fact that when the end 95 portions of the side members A are drawn inwardly sufficiently to bow out the center portions of said side members A, a slight relief will be provided between said members and the heads and base flanges of the 100 rails at the extreme ends or terminals of the rails. It is immaterial, so far as my broad idea is concerned, just where the fulcrum points γ on the side members A are located, so long as said fulcrum points are in proximity to the center bolts of the joint. 105

Having thus described my invention, what I claim, and desire to secure by Letters Patent, is:

1. A rail joint, comprising side members 110 arranged on opposite sides of the rails with their end portions spaced away from the heads of the rails and from the base flanges of the rails, said side members being so disposed that a slight relief is provided at the 115 center of the joint for the terminals or extreme ends of the rails.

2. A rail joint, comprising side members arranged on opposite sides of the rails with their end portions spaced away from the 120 heads and the base flanges of the rails, and fulcrum points on said members that contact with the heads and the base flanges of the rails at points in proximity to the center bolts of the joint.

3. A rail joint, comprising side members arranged on opposite sides of the rails with their end portions spaced away from the 125 heads and from the base flanges of the rails, said side members being provided interme- 130

diate their ends with portions that coöperate with the heads and base flanges of the rails to form fulcrum points for the rails located at each side of the space between 5 the ends of the rails and spaced away from the extreme ends of the rails.

4. A rail joint, comprising side members arranged on opposite sides of the rails with their end portions spaced away from the 10 heads and the base flanges of the rails, and portions intermediate the ends of said side members that are positioned between the heads and the base flanges of the rails and on which the rails fulcrum at separated 15 points in proximity to the center bolts of the joint.

5. A rail joint, comprising side members arranged on opposite sides of the rails with their end portions spaced away from the 20 heads and the base flanges of the rails and their intermediate portions arranged in engagement with the heads and the base flanges of the rails, the ends of said side members being drawn inwardly toward the 25 webs of the rails; for the purpose described.

6. A rail joint, comprising side members arranged on opposite sides of the rails with their end portions spaced away from the heads and the base flanges of the rails, said

side members being bowed outwardly intermediate their ends and provided with fulcrum points that contact with the heads and the base flanges of the rails at points in proximity to the center bolts of the joint. 30

7. A rail joint, comprising side members 35 arranged on opposite sides of the rails with their end portions spaced away from the heads and the base flanges of the rails and in engagement with the webs of the rails, said side members being provided intermediate 40 their ends with fulcrum points that contact with the base flanges and the heads of the rails at points far enough from the space between the ends of the rails to provide a relief for the terminals of the rails when 45 the rails are under load.

8. A rail joint, comprising side members arranged on opposite sides of the rails with their end portions spaced away from the heads and from the base flanges of the rails, 50 and their intermediate portions interposed between the heads and the base flanges of the rails, said side members being so disposed that the rails can fulcrum or rock on the same at separated points in proximity 55 to the center bolts of the joint.

HARRY F. ROACH.
